Primary Examiner — Jonathan J Han*Assistant Examiner* — Molly K. Orzechowski(74) *Attorney, Agent, or Firm* — Banner & Witcoff, Ltd.(57) **CLAIM**

The ornamental design for a shoe, as shown and described.

DESCRIPTION

FIG. 1 is a front perspective view of a shoe showing my new design;
FIG. 2 is a side view thereof; and,

FIG. 3 is a rear perspective view thereof.

The broken lines showing the six circle shaped elements and the hourglass shaped element represent eyelet elements that form no part of the claimed design. The broken lines depicting the remainder of the shoe form no part of the claimed design.

1 Claim, 3 Drawing Sheets(56)
